CLAIM

The ornamental design for a goalie target, as shown and described.

DESCRIPTION

FIG. 1 is a front elevation view of a goalie target showing our new design;

FIG. 2 is a top plan view thereof;

FIG. 3 is a bottom plan view thereof;

FIG. 4 is a rear elevation view thereof;

FIG. 5 is a left side elevation view thereof; and,

FIG. 6 is a right side elevation view thereof.

The broken lines showing the frame of a goal is for illustrative purposes only, and forms no part of the claimed design.
